SWITCH CONSTRUCTION

Newton C. Schellenger, El Paso, Tex., assignor to
 Chicago Telephone Supply Company, Elkhart,
 Ind., a corporation of Indiana

Continuation of application Serial No. 168,685,
 October 13, 1937. This application August 18,
 1939, Serial No. 290,924

19 Claims. (Cl. 200—11)

This application is a continuation of the co-pending application of Newton C. Schellenger, Serial No. 168,685, filed October 13, 1937, and covers a new and improved electric switch, and 5 more particularly, a switch of the selective multiple contact type.

While the switch of this invention is capable of a wide variety of uses, it is especially adapted for use in connection with radio tone controls 10 of the stepped type wherein any one of a series of terminals is selectively connected with a single continuously connected terminal.

Tone controls of this type are widely used in automobile radio receivers, the switch being 15 mounted in the control head or panel of the radio. In order to minimize the size of the control head, it is desired to provide a tone control switch operable concentrically with another control, such as, for example, the volume control. 20 This necessitates that the switch be provided with a hollow shaft which should not be connected into the switch circuit.

It is a further object to provide a switch of this character having a tubular shaft insulated 25 from the switch contacts and drivingly connected with the contactor of the switch in a manner obviating the possibility of binding.

It is also an object of this invention to provide 30 a switch in which a slip ring coacts with an elongated fixed contact.

It is an additional object to provide a switch of this character in which the movable selective contactor is formed integrally with the slip ring.

It is a further object to provide a construction 35 in which the slip ring is provided with indexing means coacting with the fixed contact.

In general, the tone control is a secondary control, not to be operated by the main knob but by 40 an auxiliary knob or collar adjacent to the face of the control head. This makes it necessary for the shaft of the switch to be tubular so as to permit the primary control shaft to extend through it. In many cases, this primary control shaft may carry current or be grounded so that 45 the tubular switch operating shaft must not be connected to any of the switch contacts.

The space available in an automobile radio control head, and in fact, in many so-called mid-get radios, is very limited, and hence, to be commercially acceptable, it is necessary that the 50 switch be compact in construction.

It is therefore an object of the present invention to provide a new and improved multiple contact switch of unprecedented compactness.

55 It is also an object of this invention to pro-

vide a switch in which the slip ring or movable contactor is small in size but adequately resilient to insure proper switch contact wiping action and sufficient contact pressure.

It is a further object to provide a switch small 5 in size, composed of but few parts and adapted for commercial production and use.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be 15 made as come within the scope of the claims.

The accompanying drawing illustrates one complete example of the physical embodiment of the invention constructed in accordance with the best mode so far devised for the practical 20 application of the principles thereof, and in which:

Figure 1 is a plan view of a switch constructed in accordance with this invention;

Figure 2 is a sectional view taken on line 2—2 25 of Figure 1;

Figure 3 is a transverse sectional view taken on line 3—3 of Figure 2;

Figure 4 is a sectional view taken on line 4—4 of Figure 3; and

Figure 5 is an exploded view showing the parts 30 of the switch.

Referring now particularly to the accompanying drawing in which like numerals indicate like parts, the numeral 5 designates a base formed 35 of insulating material such as sheet "Bakelite," and having terminals 6, 7, 8 and 9 secured thereto by rivets 10, 11, 12 and 13. The terminals are held against rotation about the rivets by engaging in notches formed in the edge of the base. 40

The upper heads of the rivets serve as switch contacts to be engaged by the flattened contact portion 16 of a rotatable slip ring or contactor 17. At diametrically opposite points, the ring or contactor 17 has a pair of upwardly extending 45 U-shaped portions or "humps" 18 which fit snugly in locating notches 19 in a drive disc 20. To provide for these "humps," the ring or contactor is blanked out with two straight portions tangent to and connecting two semicircular portions, the straight portions providing the stock for the "humps" so that when complete, the contactor is substantially circular.

Opposite the contact portion 16, the contactor has a rounded downwardly extending indexing 55

portion 21 adapted to engage in any one of the perforations 22, 23, 24 and 25 in an arcuate collector member or contact 26.

The collector member 26 is formed with a 5 downwardly extending lug 27 at one end which extends through an opening 28 in the base 5 to be clinched over the underside of the base, and has an attaching portion 29 at the opposite end. This portion 29 has a narrow downwardly extending part received in a notch 30 in the edge of the base, and a wider part projecting outwardly to engage under the edges of the notch and thereby coat with the lug 27 in securing the collector member 26 to the base. The extremity of 10 this latter part provides a solder lug.

The base 5 has perforations 31, 32, 33 and 34 in alignment with the openings 22, 23, 24 and 25, respectively, of the collector member 26 to insure proper contact between the indexing portion 21 of the slip ring contactor 17 by allowing it to extend down into the perforations in the base, if necessary, to effect secure engagement with the edges of the holes in the collector member.

25 The drive disc 20 is driven by a tubular shaft 35, the inner end portion of which is castellated to provide four tongues 36 which engage in notches 37 in the edge of a central hole in the drive disc. Those portions of the disc lying between the notches seat against the bottoms of the slots formed by the castellated portion of the shaft to support the disc against endwise motion with respect to the shaft in one direction.

30 The shaft projects through a central hole in the base, and a washer or spacing collar 38 interposed between the base and the drive disc, and also through a hole 39 in the lower leg 40 of a U-shaped frame 41. The base 5 rests on the lower leg 40 of the U-shaped frame, and to hold 40 these parts against relative rotation, the closed end 42 of the frame is received in a notch 43 in the edge of the base.

The upper arm 44 of the U-shaped frame extends over the drive disc and has a hole 45 in 45 which the four tongues 36 on the inner end of the shaft are rotatably received. The holes 39 and 45 in the lower and upper arms of the U-shaped frame thus provide spaced bearings for the rotatable shaft.

50 Inasmuch as the drive disc engages the under-surface of the upper arm, the resiliency of the slip ring 11 yieldingly holds the disc against the frame to thereby provide the support against which the contact pressure reacts.

55 The four tongues on the inner end of the shaft have their extremities reduced in width to form end portions 46 and shoulders 47. These reduced end portions are received in notches 48 in the edge of a central hole 49 in a washer 49, the washer seating on the shoulders 46. Consequently, by striking down the extreme ends of the tongues, as at 50, the tubular shaft is drivingly connected with the disc 20 and held against endwise motion in the frame 42.

60 Attention is directed to the fact that this manner of assembling these parts prevents binding as the length of the tongues from the bottoms of the slots therebetween to the shoulders 46 which support the washer, is slightly greater than the combined thickness of the drive disc and the frame.

The limits of rotation are defined by a stationary stop 51 extending up from the end of the upper leg of the frame to be engageable with radial lugs 52 on the washer 49.

The method of assembling the parts, while probably clear from the drawing and description, is briefly as follows.

The various terminals and the collector member are first secured to the base. The slip ring contactor 17, which is sprung transversely substantially on the axis of its U-shaped projections, is then assembled with the drive disc 20, and these parts, together with the spacing collar 38 are assembled with the base and the entirety 10 slipped between the legs of the U-shaped frame.

15 The central openings in the several parts are brought into registration and the shaft inserted therethrough, care being taken that the tongues on the end of the shaft properly enter the notches 15 in the drive disc.

The washer 49 is then applied to the extremities of the four tongues seating against the shoulders 46, whereupon the tongues are struck over to secure the parts together. All of the component parts of the unit are thus permanently located relative to each other.

20 As best shown in Figure 5, the lower leg of the U-shaped frame may be provided with a locating tongue or extension 53 to engage a fixed portion of the support on which the switch is mounted and thereby hold the frame and base against rotation.

25 From the foregoing description taken in connection with the accompanying drawing, it will be readily apparent that this invention provides an exceptionally compact switch suitable for stepped tone control in small radio receivers, and that the switch has many advantages.

30 One of these advantages results from the U-shaped locating portions on the spring slip ring or contactor. These "humps," as they may be called, serve the double function of locating the slip ring relative to the drive disc, and of adding to the resiliency of the slip ring. No 40 rivets or other weakening connections are thus necessary to properly connect the slip ring to the drive disc, so that the full width of the ring is available for resiliency.

35 Moreover, by virtue of this manner of connecting the slip ring to the drive disc, the ring is free to rock on a diametrically transverse fulcrum axis to permit the opposite portions thereof to seat firmly against the contacts and the collector member.

40 Another desirable attribute of this switch is the simplicity of its assembly, which flows from the novel manner of drivingly connecting the shaft to the drive disc and the embracing formation of the frame.

45 What I claim as my invention is:

1. In an electric switch: a base; a plurality of contacts carried by the base; a rotatable shaft extending through the base; a drive disc rotatable by the shaft and overlying the base; a substantially circular resilient contactor between the drive disc and the base, the drive disc having spaced notches therein and the resilient contactor having integral U-shaped portions fitting into said notches of the drive disc whereby the contactor is rotatable by the disc; and contact engaging portions on the resilient contactor adapted for engagement with the spaced contacts.

2. In an electric switch: a base; a plurality of stationary contacts carried by the base; a rotatable shaft extending through the base; a driver drivingly connected with the shaft and overlying the base; a substantially circular resilient contactor between the driver and the base, the driver having spaced openings therein; integral

- substantially U-shaped portions on the resilient contactor fitting in said openings of the driver so that the contactor is rotatable by the driver; contact engaging portions on the resilient contactor adapted for engagement with the stationary contacts; and a mounting frame having spaced apart legs, one of which supports the undersurface of the base, and the other of which holds down the driver, said legs having aligned 5 bearings for the shaft; the resilient contactor urging the base and driver toward said legs.
3. In an electric switch: a base; a plurality of stationary contacts carried by the base; a rotatable shaft extending through the base; a driver 10 drivingly connected with the shaft and overlying the base; a substantially circular resilient contactor between the driver and the base, the driver having spaced openings therein; integral substantially U-shaped portions on the resilient 15 contactor fitting in said openings of the driver so that the contactor is rotatable by the driver; contact engaging portions on the resilient contactor adapted for engagement with the stationary contacts; a mounting frame having spaced 20 apart legs, one of which supports the undersurface of the base, and the other of which holds down the driver, said legs having aligned bearings for the shaft; the resilient contactor urging the base and driver toward said legs; and coact- 25 ing stop means on the shaft and one leg of the frame for limiting rotation of the shaft and contactor.
4. In an electric switch: a base; a plurality of stationary contacts carried by the base; a 30 rotatable shaft extending through the base; a driver drivingly connected with the shaft and overlying the base; a substantially circular resilient contactor between the driver and the base, the driver having spaced openings therein; integral substantially U-shaped portions on the 35 resilient contactor fitting in said openings of the driver so that the contactor is rotatable by the driver; contact engaging portions on the resilient contactor adapted for engagement with the stationary contacts; and a mounting frame having 40 spaced apart legs, one of which supports the undersurface of the base, and the other of which holds down the driver, said legs having aligned bearings for the shaft; the resilient contactor urging the base and driver toward said legs; the driver being of insulating material, and insulating the resilient contactor from the shaft; and the base being of insulating material, and insulating the spaced stationary contacts from the 45 shaft.
5. In an electric switch: a base; a plurality of stationary contacts carried by the base; a rotatable shaft extending through the base; a driver drivingly connected with the shaft and overlying the base; a substantially circular resilient contactor between the driver and the base, the driver having spaced openings therein; integral substantially U-shaped portions on the 50 resilient contactor fitting in said openings of the driver so that the contactor is rotatable by the driver; contact engaging portions on the resilient contactor adapted for engagement with the stationary contacts; and a mounting frame having 55 spaced apart legs, one of which supports the undersurface of the base, and the other of which holds down the driver, said legs having aligned bearings for the shaft; the resilient contactor urging the base and driver toward said legs; the shaft being tubular and open from end to end.
6. In an electric switch of the character de- 60
- scribed: a base; a plurality of spaced contacts carried by the base; a rotatable shaft extending through the base; a drive member connected with the shaft to be rotatable thereby and overlying the base; a resilient contactor between the drive member and the base; means for drivingly connecting the contactor with said drive member whereby the contactor is rotated by the drive member; contact engaging portions on the resilient contactor adapted for engagement with the spaced stationary contacts; and a U-shaped frame having one leg below the base and the other leg above the drive member, said legs having aligned bearings for the shaft; the resilient contactor urging the base and drive member 65 against the inner faces of the legs.
7. In an electrical control device, the combination of: a base; a rotatable shaft extending through the base; a drive member connected with the shaft to be rotatable thereby, said 70 drive member overlying the base; a resilient contactor between the drive member and the base; a driving connection between the contactor and the drive member; and a U-shaped frame having one leg below the base and the other leg above the drive member, said legs having aligned bearings for the shaft; the resilience of the contactor urging the base and drive member outwardly toward the inner faces of the legs.
8. In an electrical control device, the combination of: a base; a rotatable shaft extending through the base; a drive member connected with the shaft to be rotatable thereby, said drive member overlying the base; a resilient contactor 75 between the drive member and the base; a driving connection between the contactor and the drive member; a U-shaped frame having one leg below the base and the other leg above the drive member, said legs having aligned bearings for the shaft; the resilience of the contactor urging the base and drive member outwardly toward the inner faces of the legs; a stop secured to the shaft adjacent to one leg of the frame; and a coacting stop carried by said leg of the frame.
9. In an electrical control: a base; a rotatable shaft extending through the base, portions of the shaft being cut away; a drive member having portions fitting into the spaces of said cut away portions in the shaft to provide a nonrotatable driving connection between the shaft 80 and drive member; a resilient contactor between the base and the drive member; a driving connection between the contactor and the drive member; a U-shaped frame having one leg below the base and the other leg above the drive member, said legs having aligned bearings for the shaft; the drive member engaging the inner face of the adjacent leg of the frame for limiting axial movement of the shaft relative to the frame in one direction; and a stop member secured to 85 the shaft adjacent to the outer face of said leg for limiting movement of the shaft relative to the frame in the opposite direction.
10. In an electrical control: a base; a rotatable shaft extending through the base, portions of the shaft being cut away; a drive member having portions fitting into the spaces of said cut away portions in the shaft to provide a nonrotatable driving connection between the shaft and drive member; a resilient contactor between the 90 base and the drive member; a driving connection between the contactor and the drive member; a U-shaped frame having one leg below the base and the other leg above the drive member, said legs having aligned bearings for the shaft; 95

the drive member engaging the inner face of the adjacent leg of the frame for limiting axial movement of the shaft relative to the frame in one direction; a stop member secured to the shaft 5 adjacent to the outer face of said leg for limiting movement of the shaft relative to the frame in the opposite direction; shoulders on said stop member; and a stop on said adjacent leg of the frame coacting with said shoulders to limit 10 rotary movement of the shaft.

11. In an electric switch: a base; stationary contact means carried by the base; a drive member adjacent to the base; means for moving the drive member, said drive member having spaced 15 openings; a unitary resilient movable contactor between the drive member and the base, said contactor being approximately circular in shape and having integral substantially oppositely located raised portions engaging in said openings 20 of the drive member; portions of said movable contactor intermediate the raised portions thereof being located for engagement with the stationary contact means.

12. As an article of manufacture, a resilient 25 contactor for use in radio controls comprising: a single ring stamped from resilient sheet metal having substantially diametrically opposite portions thereof bulged abruptly across the full width of the ring and in the same direction to 30 provide substantially U-shaped humps on one face of the ring to provide abutments engageable in suitable recesses formed in a driving member with which the contactor may be connected; and said contactor being sprung about an axis 35 passing through said bulges to project its portions intermediate the bulges outwardly of the plane of said bulges to be resiliently engageable with suitably disposed contacts.

13. As an article of manufacture, a contactor 40 for electrical control units of the type used in radio comprising: a continuous ring stamped from resilient sheet metal and having substantially uniform width throughout its circumference and having substantially diametrically opposite U-shaped bulges projecting in the same direction from the general plane of the contactor to provide driving lugs by which the contactor may be rotated and to provide relatively long spring members within a small space; and 45 means on the portions of the ring lying between the bulges adapted for transient engagement with suitably placed stationary contacts.

14. In a multiple contact switch of the character described: a flat base of insulating material 50 having a hole therethrough; a plurality of stationary contacts on one face of the base, said contacts being arranged in an arc concentric with the hole; a single collector contact on said face of the base diametrically opposite said stationary contacts and having a portion lying flat on said face of the base, said portion having holes therethrough arranged in an arc concentric with the hole and substantially diametrically opposite the stationary contacts; an attaching ear on 55 one end of said portion passing through the base and clinched over the opposite face thereof to secure one end of said portion to the base; an extension on the opposite end of said portion having a narrow part received in a notch in the edge of the base, and a wider part engaging the edges of the notch at the underside of the base; a contactor having a part riding on said portion of the collector contact and another part engageable with the stationary contacts; and an 60 operating shaft connected with the contactor for

turning the same to selectively electrically connect any one of said stationary contacts with the collector contact.

15. In a control unit: a metal frame having a hole; an operating shaft journaled therein, said shaft having circumferentially spaced tongues 5 at its portion journaled in the frame, said tongues having their extremities reduced in width to provide shoulders; a carrier for the control part to be rotated by the shaft having a hole 10 through which the shaft projects and having portions projecting radially from the edge of the hole and engaging in the space between said tongues, said radial projections being seated on the bottom of the slots defined by the spaces 15 between the tongues and said carrier engaging one face of the frame; a washer engaging the opposite face of the frame and having the reduced end portions of the tongues received in openings therein so that the washer seats on 20 the shoulders of the tongues; and the extreme end portions of the tongues being bent down over the washer to hold said parts assembled, the length of the tongue portions between the bottom of the spaces therebetween to the shoulders being slightly greater than the combined thickness of the carrier and the adjacent wall 25 of the frame so that the parts are secured in assembled relation without binding.

16. In a control of the character described: a frame having a wall provided with a hole; a tubular shaft having an end portion received in said hole, said end portion of the shaft being castellated to provide circumferentially spaced tongues and slots therebetween, the bottoms of 30 all of the slots lying substantially in a common plane normal to the axis of the shaft, and said tongues having their end portions reduced in width to provide narrow extremities and shoulders; a carrier for the rotatable portion of the 35 control having a central hole to receive the tubular shaft and engaging one face of said wall of the frame; lugs extending inwardly from the edge of the hole in said carrier disposed in the bottoms of said slots between the tongues; a washer 40 engaging the opposite face of said wall of the frame and having openings through which the narrow end portions of the tongues project so that the washer seats on the shoulders, said narrow end portions being bent over to secure 45 the shaft and the rotatable carrier assembled with the wall; and the length of said tongues between the bottoms of the slots and the shoulders being slightly greater than the combined thickness of the carrier and the adjacent portion 50 of the frame wall so as to preclude binding of said parts when the narrow end portions of the tongues are clinched down.

17. In a control of the character described: a frame having a wall provided with a hole there- 55 through; a rotatable operating shaft projecting through said hole; a carrier for the rotatable portion of the control receiving support from one face of said wall and having a hole through which the shaft projects; cooperating means on 60 said carrier and the shaft preventing endwise movement of the shaft through the carrier in a direction toward the frame wall; a washer fitted over the end of the shaft projecting from the opposite face of the frame wall and receiv- 65 ing support from said opposite face of the frame wall; cooperating means on said washer and shaft preventing endwise motion of the shaft through the washer in the same direction that 70 endwise motion is prevented between the car- 75

rier and shaft, said two motion limiting means being spaced apart a distance slightly greater than the combined thickness of the carrier and the adjacent frame wall; and means on the shaft 5 outwardly of the washer to confine the washer between it and the second named motion limiting means to thereby hold said parts operatively assembled with the shaft and said carrier freely rotatable with respect to the frame.

10 18. In a control of the character described: a substantially U-shaped frame having spaced apart legs provided with aligned holes; a shaft journaled in both of said holes; a carrier for the rotatable portion of the control mechanism having a hole through which the shaft projects and engaging the inner face of one leg of the frame; cooperating means on the carrier and shaft drivingly connecting the same and preventing endwise motion of the shaft relative thereto in a 15 direction toward the adjacent leg of the frame; a washer engaging the outer face of said leg of the frame and receiving the end portion of the shaft; cooperating means on said washer and shaft limiting endwise motion of the shaft in the same direction that endwise motion of the shaft is limited by said first named motion limiting means, the space between said two sets of motion limiting means being slightly greater than 20 the combined thickness of the carrier and the adjacent wall of the frame; means on the shaft engaging over the washer to secure said shaft, carrier, and washer assembled with the frame in a manner whereby the shaft and carrier are 25 freely rotatable in the frame; and control mech-

anism confined between the carrier and the other leg of the frame.

19. In a control of the character described: a substantially U-shaped frame having spaced apart legs provided with aligned holes; a tubular shaft open from end to end journaled in both of said holes; a carrier for the rotatable portion of the control mechanism having a hole through which the shaft projects and engaging the inner face of one leg of the frame; cooperating means 10 on the carrier and shaft drivingly connecting the same and preventing endwise motion of the shaft relative to the carrier in a direction toward the adjacent leg of the frame; a washer engaging the outer face of said leg of the frame and receiving the end portion of the shaft; cooperating means on said washer and shaft nonrotatably connecting the same and limiting endwise motion of the shaft in the same direction that endwise motion of the shaft is limited by said 20 first named motion limiting means, the space between said two sets of motion limiting means being slightly greater than the combined thickness of the carrier and the adjacent wall of the frame; means on the shaft engaging over the 25 washer to secure said shaft, carrier, and washer assembled with the frame in a manner leaving the shaft and carrier freely rotatable in the frame; control mechanism confined between the carrier and the other leg of the frame; and 30 cooperating stops on the washer and the adjacent leg of the frame for limiting rotation of the shaft and the rotatable portion of the control mechanism.

NEWTON C. SCHELLENGER. 35
